Primary Examiner — Kevin K Rudzinski

(57) **CLAIM**

The ornamental design for a cartridge for 3D printing, as shown and described.

DESCRIPTION

FIG. 1 is a perspective view of cartridge for 3D printing showing my new design;

FIG. 2 is a top view thereof;

FIG. 3 is a right side view thereof;

FIG. 4 is a front view thereof;

FIG. 5 is a left side view thereof;

FIG. 6 is a rear view thereof; and,

FIG. 7 is a bottom view thereof.

The broken lines shown in the drawings depict portions of the cartridge for 3D printing that form no part of the claimed design.
